DESIGN FOR AN APPLIQUÉ EMBLEM OR SIMILAR ARTICLE

Walter P. Burn and Helen Jurkops, Washington,
D. C., assignors to United States of America, as
represented by James M. Landis, United States
Director of Civilian Defense, Office of Civilian
Defense, and his successors in office

Application February 11, 1942, Serial No. 105,753

Term of patent 7 years

To all whom it may concern:

Be it known that we, Walter P. Burn and
Helen Jurkops, citizens of the United States and
residents of Washington, in the District of Co-
lumbia, have invented a new, original, and orna-
mental Design for an Appliquéd Emblem or Similar
Article, of which the following is a specification,
reference being had to the accompanying draw-
ing, forming part thereof.

Fig. 1 is a front elevational view of an appliquéd
emblem showing my new design;

Fig. 2 is an edge view thereof.

While we have shown our design in the form
of an appliquéd emblem it is understood that the
same may be embodied in other similar articles
such as badges, placards, banners, buttons, pins,
arm pieces, head gear, and the like without de-
parting from the spirit of our invention.

We claim:

The ornamental design for an appliquéd emblem
or similar article, as shown and described.

WALTER P. BURN.
HELEN JURKOPS.
